CORRUGATED PIPE

Ernest J. Maroschak, Roseboro, N.C., assignor to
Plastic Tubing, Inc.

Filed Dec. 5, 1973, Ser. No. 422,020

Term of patent 14 years

Int. Cl. D23—01

U.S. Cl. D23—45

FIG. 1

FIG. 2

FIG. 3

FIG. 4

FIG. 6

FIG. 5

FIG. 7

Fig. 10

Fig. 11

Fig. 13

Fig. 12

Fig. 14

FIG. 1 is a top plan view of a corrugated pipe showing my new design;

FIG. 2 is a side elevational view thereof;

FIG. 3 is a bottom plan view thereof;

FIG. 4 is an end view taken from the left of FIG. 1;

FIG. 5 is a sectional view taken along line 5—5 of FIG. 2;

FIG. 6 is a sectional view taken along line 6—6 of FIG. 2;

FIG. 7 is a sectional view taken along line 7—7 of FIG. 3;

FIG. 8 is a top plan view of a second embodiment of the corrugated pipe shown in FIG. 1;

FIG. 9 is a side elevational view of FIG. 8;

FIG. 10 is a bottom plan view of FIG. 8;

FIG. 11 is an end view taken from the left of FIG. 8;

FIG. 12 is a sectional view taken along line 12—12 of FIG. 9;

FIG. 13 is a sectional view taken along line 13—13 of FIG. 9;

FIG. 14 is a sectional view taken along line 14—14 of FIG. 10;

FIG. 15 is a bottom plan view of a third embodiment of the corrugated pipe shown in FIG. 1 and the top and side thereof corresponds with the top and side of the first embodiment except for the presence of holes in the side of this embodiment;

FIG. 16 is an end view taken from the left of FIG. 15;

FIG. 17 is a sectional view taken along line 17—17 of FIG. 15;

FIG. 18 is a sectional view taken along line 18—18 of FIG. 15;

FIG. 19 is a sectional view taken along line 19—19 of FIG. 15;

FIG. 20 is a bottom plan view of a fourth embodiment of the corrugated pipe shown in FIG. 1 and the top and side thereof corresponds with the top and side of the second embodiment except for the presence of holes in the side of this embodiment;

FIG. 21 is an end view taken from the left of FIG. 20;

FIG. 22 is a sectional view taken along line 22—22 of FIG. 20;

FIG. 23 is a sectional view taken along line 23—23 of FIG. 20; and

FIG. 24 is a sectional view taken along line 24—24 of FIG. 20.

A portion of the corrugated pipe has been broken away in FIGS. 1, 2, 3, 8, 9, 10, 15 and 20 to indicate indeterminate length.

I claim:

The ornamental design for a corrugated pipe, substantially as shown and described.
